UNITED STATES PATENT OFFICE.

ALBERT H. FIELD, OF NEW YORK, N. Y.

COIN CASE.

Application filed February 6, 1922. Serial No. 534,491.

To all whom it may concern:

Be it known that I, ALBERT H. FIELD, a citizen of the United States, residing at New York, in the county of New York and State of New York, have invented certain new and useful Improvements in Coin Cases; and I do declare the following to be a full, clear, and exact description of the invention, such as will enable others skilled in the art to which it appertains to make and use the same.

My invention relates to improvements in coin cases and more particularly to those of small compact size to be conveniently carried in the user's pocket, and the principal object of the invention is to provide an extremely simple and inexpensive, yet a highly desirable coin carrying device by means of which a number of coins of the same denomination may be conveniently carried and discharged one at a time for use, simply by turning a disk or like form of coin delivery device.

In the preferred form of my invention, a relatively thick disk is fixedly mounted in a shallow casing and is formed with a plurality of openings to contain stacks of coins, the coin-delivery disk being interposed between the other disk or coin magazine and the bottom of the casing and having its edge accessible at a cut-away portion of the casing, so that it may readily be turned, another object of the invention being to provide novel means for holding this disk against accidental rotation.

In order that the magazine may be conveniently filled with coins, the casing is preferably provided with a cover plate having an opening adapted to be successively registered with the openings of the magazine disk, and a further aim of the invention is to provide a single device carried by the casing for holding this cover plate and the coin delivery disk against turning except when required.

With the foregoing and minor objects in view, the invention resides in the novel subject matter hereinafter described and claimed, the descriptive matter being supplemented by the accompanying drawing.

Figure 1 is a perspective view of a coin carrier constructed in accordance with my invention.

Figures 2 and 3 are transverse sectional views as indicated by lines 2-2 and 3-3 respectively of Fig. 1.

Figure 4 is a disassembled perspective view showing the casing, the coin delivery disk, the magazine disk and the cover plate in juxtaposition.

Figure 5 is an edge view showing a different form of cover plate which may be used in lieu of the plate above referred to.

In the drawings above briefly described, the numeral 1 designates a shallow casing which is of substantially circular form although it is partially cut away as indicated at 2, for a purpose to appear. Within the casing 1 is a comparatively thick magazine disk 3 having a plurality of vertical openings 4 to receive stacks of coins. The disk 3 is spaced above the bottom of the casing 1 a distance equal to the thickness of one of the coins to be contained by the openings 4 and this disk is secured in this position by any suitable means such as screws 5 passing through the wall of the casing into said disk. The space between the disk 3 and the bottom of the casing is occupied by a coin delivery disk 6 having a plurality of openings 7 into which the coins are adapted to drop one at a time from the openings 4, so that when said delivery disk 6 is turned to the proper extent, a coin will be moved to the cut-away portion 2 of the casing and dropped therethrough. The edge of the disk 6 is suitably roughened as indicated at 8 and a portion of the magazine disk is preferably cut away as indicated at 9 at the cut-away portion of the casing, in order that said roughened edge may be more accessible for turning the disk.

Resting rotatably upon the edge of the casing 1 and the magazine disk 3, is a cover plate 10 which is held in place by a central bolt or other fastener 11 which extends through the disk, through the casing bottom, and through the intervening parts. The cover plate 10 is formed with a coin entrance opening 12 which normally overlies an imperforate portion of the magazine disk 3 as shown in Fig. 3, but by turning the plate 10, the opening 12 may be successively alined with the openings 4 so that the latter may be filled with coins.

In order to hold the coin delivery disk 6 and the cover plate 10 against accidental rotation, I provide any suitable means such as a single U-shaped spring metal clip 13 which is carried by the casing and is by preference pivoted thereto as indicated at 14. When this clip is swung outwardly

from the position shown in Fig. 1 both disks are free to rotate but when the clip is in operative position, said disks are held against accidental turning.

5 In Fig. 5 I have illustrated a slightly different form of construction, in that the cover plate 10^a is threaded upon the casing 1 instead of being mounted in the manner previously described. In place of this threaded 10 connection, it will be understood that the flange of the cover plate could merely have a frictional engagement with the casing. In fact, any suitable cover may be used in connection with the features of novelty 15 above described.

The openings 4 are filled with coins, either by rotating the plate 10 or by removing any other form of cover plate with which the casing may be provided and when this cover 20 is restored to its normal position, the device is in readiness for use. Ordinarily, one of the openings 7 of the disk 6 stands at the cut-away portion 2 of the casing 1, so that the other openings are filled with coins from 25 the openings 4. Thus, when the clip 13 is released and the delivery disk 6 is rotated to the proper extent, one of these coins will be discharged from the casing and the opening which was previously positioned at the 30 cut-away casing portion 2, will be filled from one of the openings 4. In operating the device, it is preferably held in one hand with the palm of the latter positioned upwardly. Thus, by turning the disk 6 with 35 the other hand, the coin or coins will be discharged into the palm of the hand first mentioned.

Since excellent results have been obtained with the details disclosed, they are by preference followed, but it is to be understood that within the scope of the invention as claimed, numerous minor changes may be made.

I claim:

45 1. A coin holder comprising a magazine having a vertical passage to contain a stack of coins, a support spaced downwardly from said magazine a distance equal to the thickness of a coin, and a rotatable coin delivery disk between said magazine and support adapted when rotated to move the bottom coin from the stack to a point at which it will drop from the support.

55 2. A coin holder comprising a magazine having a vertical passage to contain a stack of coins, a support spaced downwardly from said magazine a distance equal to the thickness of a coin, and a rotatable coin delivery disk between said magazine and support having a plurality of openings adapted to receive coins from said stack and convey

them to a point at which they will drop from said support.

3. A coin holder comprising a casing having its bottom and wall partly cut away, a magazine disk secured in said casing and having a plurality of vertical openings adapted to contain stacks of coins, said magazine disk being spaced from said bottom a distance equal to the thickness of a coin, and a rotatable coin delivery disk in said casing between the bottom of the latter and said magazine disk, said coin delivery disk having a plurality of openings adapted to receive coins from said stacks and convey them to the cut-away portion of the casing bottom, said coin delivery disk having its edge exposed by said cut-away portion of the casing wall, whereby this disk may be easily rotated.

4. A coin holder comprising a casing having its bottom and wall partly cut away, a magazine disk secured in said casing and having a plurality of vertical openings adapted to contain stacks of coins, a rotatable cover plate for said casing movable to give access to said openings of the magazine disk for filling the same, a rotatable coin delivery disk in the casing between the bottom of the latter and said magazine disk for delivering coins from the stacks to the cut-away portion of said casing bottom, said coin delivery disk having its edge exposed at said cut-away portion of the casing wall whereby it may be easily rotated, and a holding member carried by the casing and engaging said coin delivery disk and said cover plate to hold them against accidental rotation.

5. A coin holder comprising a casing having its bottom and wall partly cut away, a magazine disk secured in said casing and having a plurality of vertical openings adapted to contain stacks of coins, a rotatable cover plate for said casing movable to give access to said openings of the magazine disk for filling the same, a rotatable coin delivery disk in the casing between the bottom of the latter and said magazine disk for delivering coins from the stacks to the cut-away portion of said casing bottom, said coin delivery disk having its edge exposed at said cut-away portion of the casing wall whereby it may be easily rotated, and a U-shaped spring metal clip connected pivotally with the casing and normally embracing said cover plate and said coin delivery disk to hold them against accidental rotation.

In testimony whereof I have hereunto set my hand.

ALBERT H. FIELD.
